UNITED STATES PATENT OFFICE.

LEONARD F. HEITZ, OF LAKE MILLS, WISCONSIN, ASSIGNOR TO THE CREAMERY PACKAGE MFG. COMPANY, OF CHICAGO, ILLINOIS, A CORPORATION OF ILLINOIS.

REVOLUTION INDICATOR FOR CHURNS.

Application filed April 17, 1922. Serial No. 553,776.

To all whom it may concern:

Be it known that I, LEONARD F. HEITZ, a citizen of the United States, residing at Lake Mills, in the county of Jefferson and State 5 of Wisconsin, have invented certain new and useful Improvements in Revolution Indicators for Churns, of which the following is a specification.

The invention relates to devices for timing 10 the operation of rotary churning, and more particularly to a device for signaling the completion of a predetermined number of churn revolutions.

In the processes of churning and working 15 butter, the time consumed in accomplishing the desired results varies appreciably with variable conditions in the cream and with other conditions well known to butter workers.

20 The timing of these operations in the rotary type of commercial churn is usually controlled by operating the churn for a specific number of revolutions previously determined from the conditions mentioned.

25 The use of automatic means for recording the predetermined number of revolutions and signaling their completion is obviously desirable, as it permits the operator's occupation with other duties until signalled.

30 The principal object of this invention is to provide an automatic device of improved construction which may be operatively attached to a churn, or other apparatus having revoluble or reciprocal parts to actuate the device, and which may be selectively set to register the desired number of recurring movements and sound a signal when they are completed.

Another object is to provide an indicating 40 signal device of this character in which there are few operating parts, and which is of simple substantial construction capable of effective continuous operation with a minimum of wear and adjustment.

45 Other objects and advantages will be apparent in the following description of a preferred embodiment of my invention as applied to a rotary churn, and which I have illustrated in the accompanying drawings.

50 In the drawings, Fig. 1 is a side elevation of the device and fragments of the associated churn parts. Fig. 2 is a front elevation of the same. Fig. 3 is a detail of one of the parts.

The device comprises a standard 1 having 55 a base portion 2 suitable for attachment to a stationary part of a churn. As illustrated herein the base 2 is secured to the bearing cap 3 of the gudgeon bearing supporting one end of the churn drum. The base may be arranged to receive the cap screws 4 by 60 which the bearing cap is secured to the main portion 5 of the bearing, being thus rigidly supported.

The upright portion of the standard 1 carries a pivot pin 6 having a non-rotative longitudinally movable bearing support in the standard and extending through the latter.

70 A dial 7 is rotatively mounted on the forward end of the pin 6, and is provided with a hub 8 having a rear face of substantial area contacting a similar face provided on the standard 1. The dial is retained on the pin 6 by the flanged head 9 formed on the end of the pin, and its hub 8 is held in resiliently tensioned contact with the standard 1 by means of the compression spring 10 confined between the opposite side of the standard 75 and the adjustable stop or nut 11 threaded on the rear end of the pin 6. The spring tension may be so adjusted as to cause sufficient friction between the abutting faces of the dial hub and the standard to prevent the dial from over-running when actuated as 80 hereinafter described.

The upper end of the standard 1 is preferably bifurcated to provide a pair of spaced supports 12 which carry a reciprocatory bar 13 positioned substantially parallel to the 90 plane of the dial 7. One end of the bar preferably terminates adjacent the periphery of the dial, the other end extending toward the churn drum and terminating near the path of the gudgeon supporting frame.

95 Herein is illustrated an arm 14 of a gudgeon support, upon the face of which is preferably mounted a cam member 15 suitably secured thereto as by bolts 16. The cam 15 is located so that with each revolution of the gudgeon it engages and actuates the reciprocatory bar 13. The latter may be provided with an anti-friction roller 17 pivoted in the end of the bar for engagement by the cam.

100 The bar 13 is normally retained in position for engagement by the cam 15 by resilient means preferably comprising a

compression spring 18 abutting the inner face of the outer support 12 and oppositely confined by a cross pin 19 fixed in the bar 13.

A pawl 20 is pivotally secured on the end of the bar 13 adjacent the dial, as by means of the stud screw 21, its free end extending over and in operative engagement with the periphery of the dial.

The dial 7 is provided preferably about 10 its outer periphery with a series of ratchet teeth 22 spaced so that the engaging pawl 20 rotates the dial through the distance of one tooth with each reciprocation of the bar 13. The face of the dial may be marked 15 with numerals 23 indicating at intervals the number of teeth from a given point 0.

Suitable means for actuating an alarm 20 may be associated with the dial. Herein is illustrated a cam 24 mounted on the rear face of the dial. A bell 25 of any suitable 25 construction operable to be sounded by the actuation of a contact member, is preferably mounted on the standard 1 with its contact member 26 extending adjacent the rear face of the dial in position to be actuated by the cam 24 when the 0 point on the periphery of the dial is in register with the pawl 20.

In operation the dial 7 may be turned 30 manually to bring the numeral indicating the desired number of revolutions for the churn operation into registering engagement with the pawl 20. Then upon starting the churn, the reciprocating bar 13 rotates the dial one tooth for each revolution of the churn, the frictional contact between the dial hub and the standard holding the dial against reverse movement by the return of the pawl and also preventing the 35 dial from over-running the forward movement of the pawl.

When the series of teeth have been advanced by the pawl to the 0 point, the alarm bell is automatically actuated, signalling the operator that the churning or 45 working operation is completed and requires his attention.

The churn may be operated without actuating the dial by securing the bar 13 in inoperative position. This may be accomplished by means of a pin 27 (Fig. 3) having 50 a suitable hand knob 28 and which is

insertable in a cross opening 29 positioned in the bar 13 so that with the latter drawn forward to expose the opening 29 between the supports 12 the insertion of the pin 27 serves to secure the roller 17 out of the path of the cam 15.

It will now be apparent that I have provided a simple durable and effective device for the purpose set forth.

I claim as my invention:

1. In combination with a churn having a rotary drum, a stationary standard, a dial pivoted on said standard and having ratchet teeth, a longitudinally slidable reciprocating bar supported by said standard, a cam carried by said drum, said bar extending into the path of said cam and being adapted for longitudinal movement by 70 contact therewith, a pawl pivoted on said bar and extending into overlying engagement with said ratchet teeth, said pawl being operable to rotate said dial a limited degree with each movement of said bar, 75 a signal device and means on the dial arranged to actuate said signal device at a certain position of said dial.

2. A device of the class described comprising a stationary standard, a rotatable 80 dial having radial ratchet teeth around its periphery, a pivot support for said dial having a bearing in said standard, said pivot support being axially movable and having spring tensioned means for retaining said dial in frictional lateral bearing contact with said standard, a longitudinally slidable bar having its bearing support in said standard and movable on an axis substantially parallel to the plane of said 85 dial, a pawl pivotally supported on one end of said bar and extending laterally into operative engagement with the ratchet teeth of said dial, the other end of said bar being adapted for actuation by a cam carried 95 by a rotating body whereby said pawl effects the intermittent rotation of said dial a tooth at a time, a signal device mounted on said standard, and means on the dial arranged to actuate said signal device at a 100 certain position of said dial.

In witness whereof, I have hereunto set my hand.

LEONARD F. HEITZ.
